CLAIM

The ornamental design for a top of a vehicle air filter, as shown and described.

DESCRIPTION

FIG. 1 is a top perspective view of the top of a vehicle air filter showing the new design;

FIG. 2 is a top plan view thereof;

FIG. 3 is a side elevational view thereof, the opposite side being a mirror image of that shown; and,

FIG. 4 is a cross sectional view thereof taken along line 4—4 in FIG. 2.

The broken lines are shown for illustrative purposes only and form no part of the claimed design.
